UNITED STATES PATENT OFFICE.

ARTHUR CARD, OF LOS ANGELES, CALIFORNIA.

PUMP.

1,326,024.

Specification of Letters Patent.

Patented Dec. 23, 1919.

Application filed July 29, 1918. Serial No. 247,270.

To all whom it may concern:

Be it known that I, ARTHUR CARD, a citizen of the United States, and a resident of Los Angeles, in the county of Los Angeles 5 and State of California, have invented a new and Improved Pump, of which the following is a full, clear, and exact description.

My invention relates particularly to that type of pumps employing a walking beam 10 and a vertical reciprocating pump rod actuated thereby.

General objects of my invention are to provide a pump of the indicated character in which the walking beam is so mounted 15 and actuated as to vibrate on a center shifting to and from the vertical line of the pump rod in addition to the vibrating movement of the beam in a vertical plane; and to provide guide means for said beam in its 20 vertical vibratory movements and for the pin constituting the shifting center of the beam, whereby the pump rod will be given a direct rectilineal reciprocating movement without friction and without the provision 25 of guide means for said rod.

Reference is to be had to the accompanying drawings forming a part of this specification, it being understood that the drawings are merely illustrative of one example 30 of the invention.

Figure 1 is a side elevation of a pump embodying my invention;

Fig. 2 is a plan view thereof;

Fig. 3 is a detail cross section on the line 35 3—3, Fig. 2;

Figs. 4 and 5 are cross sections respectively on the line 4—4 and 5—5, Fig. 1;

Fig. 6 is a longitudinal vertical section 40 on the line 6—6, Fig. 2, showing the walking beam approximately at the end of the upstroke of the pump rod;

Fig. 7 is a view similar to Fig. 6 showing the positions of the parts with the walking beam at the limit of the downward stroke 45 of the pump rod.

In carrying out my invention in accordance with the illustrated example a pump frame 10 of suitable form is mounted on a base 11 and the pump rod 12 actuated in 50 a manner hereinafter described, is adapted to have vertical rectilineal reciprocating movement through said frame and through a vertical hole 13 in the base 11.

The pump rod 12 is connected with a 55 walking beam 14 between the ends of the latter and said beam is mounted to vibrate

in the frame 10 about a center shiftable longitudinally of the frame toward and from the vertical path of movement of the pump rod. In the illustrated example the 60 fulcrumed end of the beam 14 is formed with a hub or enlargement 15 snugly accommodated between standards 10^a in the frame. A pin 16 constituting the fulcrum of the beam and its shifting center of movement 65 extends transversely to the beam at the hub 15 and projects at its ends into longitudinal slots 17 so that the pin may move longitudinally of the frame as the beam vibrates. In addition to the slots 17 the standards 10^a 70 have longitudinal grooves 19 extending around the sides and about the ends of the slots 17 and adapted to receive suitable guide elements here shown as rollers 18.

In addition to the guide means for the 75 shifting center pin 16 of the beam 14, I provide means to guide the beam in its vertical vibratory movements and acting to shift the beam and its fulcrum pin 16 independently of the pump rod, for which purpose 80 use is made of approximately upright guides designated generally by the numeral 20 formed on the frame 10 forward of the longitudinal slots 17 and grooves 19, and said guides 20 are formed with arcuate slots 85 21 and arcuate grooves 22 extending at the sides and ends of the slots. A transverse guide pin 23 extends through the beam 14 and projects at its ends into the slots 21 to have guided movement therein. Also on 90 said pin 23 guide elements are provided preferably in the form of rollers 24 traveling in grooves 22, as best seen in Fig. 4. The pin 23 passes through a hub or enlargement 26 formed on the beam 14 and 95 is accommodated between the spaced guides 20. The standards 10^a and guides 20 are integral with each other through the medium of webs 25 forming part of the frame 10 and said webs and the standards 10^a are 100 braced by transverse bolts or rivets 25^a, in the illustrated example.

The drive means for the pump includes any suitable drive shaft 27 here shown as having a pulley 28 adapted to receive a belt 105 from any convenient source of power (not shown). The drive shaft in the illustrated example has pinions 30 that mesh with gear wheels 31 at opposite sides of the plane of vibration of the walking beam 14, said 110 wheels being mounted on transverse stud shafts 32 turning in suitable bearings 33.

The two pinions and gear wheels at opposite sides are to balance the drive. A crank pin 34 is common to the two gear wheels 31 and 34 is common to the two gear wheels 31 and 34 passes transversely through a longitudinal slot 35 in the beam 14, said slot extending at opposite sides of the pump rod 12, so that the crank pin 34 may have movement across a line constituting an extension of the longitudinal axis of the pump rod. On the crank pin 34 additional guide means is provided to engage the beam, and preferably consisting of a roller 36 operating in a groove 37 in the beam and following the lines of the slot 35. The upper side of the beam 14 at the slot 35 is formed by a detachable member 14^a suitably secured by bolts 14^b or the like to permit the ready insertion and removal of the crank pin 34.

With the described arrangement it will be seen that the turning of the driven wheels 31 carries the crank pin 34, and the movement of the crank pin 34 about the axis of said wheels causes said pin to traverse said slot 35 so that the crank pin passes alternately forward and back of the pump rod and thereby gives vibratory movement to the beam 14, whereby to reciprocate the pump rod. As the beam is thus vibrated the pin 23 and rollers 24 engage the slots 21 and 20 grooves 22 of the guides 20 and the curved path thus determined for the said pin and rollers causes the beam and the fulcrum pin 16 to be shifted relatively to and from the rectilineal path of the pump rod so that the pivotal connection between the pump rod and beam is caused to travel in a direct line, thereby relieving the pump rod of lateral strain and permitting it to have direct rectilineal movement. At the same time the shifting fulcrum pin 16 is afforded guided movement in the slots 17.

In practice, the size of the walking beam, its point of connection with the pump rod, the size and curvature of slot 21, as well as other details will be determined according to the conditions under which the pump is designed to operate with respect to the depth of the well and like factors.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim as new, and desire to secure by Letters Patent:

1. A pump of the class described including a pump rod adapted to have rectilineal reciprocating movement, a walking beam to which said rod is pivotally connected, said beam having a longitudinal slot extending therein at both sides of the pivot of the pump rod, a driven revolute element, a crank pin on said element engaging said beam in said slot to travel along the latter back and forth at each revolution of said element, shiftable fulcrum means for said beam, a fixed curved guide, and means on the walking beam and engaging said guide to shift the beam and its fulcrum during the revolution of said driven element to maintain the pivotal connection between the walking beam and the pump rod in line with the rectilineal path of the pump rod.

2. A pump of the class described comprising a pump rod adapted to have rectilineal reciprocating movement, a walking beam to which said rod is pivotally connected, said beam having a longitudinal slot extending therein, a driven revolute element, a crank pin on said element engaging said beam in said slot to travel along the latter back and forth at each revolution of said element, a base for supporting the revolute element, said base being provided with guide slots, means carried by said walking beam to slide in said slots, one of said means constituting a movable fulcrum for said walking beam, whereby the pivotal connection between the walking beam and the pump rod is maintained in line with the longitudinal axis of the rod.

3. A pump of the class described comprising a pump rod adapted to have rectilineal reciprocating movement, a walking beam to which said rod is pivotally connected, said beam having a longitudinal slot extending therein, a driven revolute element, a crank pin on said element engaging said beam in said slot to travel along the latter back and forth at each revolution of said element, a base for supporting the revolute element, a fulcrum slidable toward and away from the longitudinal axis of the pump rod, a fixed curved guide, and means carried by the walking beam for engaging the curved guide.

ARTHUR CARD.
